UNITED STATES PATENT OFFICE.

NICOLAY NELSON, OF WAUKEGAN, ILLINOIS, ASSIGNOR TO BLATCHFORD CALF MEAL COMPANY, OF WAUKEGAN, ILLINOIS, A CORPORATION OF ILLINOIS.

GRINDING BEATER.

Application filed December 18, 1920. Serial No. 430,399.

To all whom it may concern:

Be it known that I, NICOLAY NELSON, a citizen of the United States, residing at Waukegan, in the county of Lake and State 5 of Illinois, have invented certain new and useful Improvements in Grinding Beaters, of which the following is a specification.

This invention relates to a machine for reducing to a fine even and soft product, all 10 kinds of grains, seed, screenings, hulls, spices, etc., and the principal object of the invention is to deliver a uniformly ground product of any desired degree of fineness in one operation. The invention consists in 15 the novel construction, combination and arrangement of the several parts.

In the accompanying drawing, Fig. 1 is a sectional view of a machine constructed in accordance with the principles of this invention as taken on the line 1—1 of Fig. 2 when it is in operation; Fig. 2 is a sectional plan view of such a machine taken on the line 2—2 of Fig. 1; and Figs. 3 and 4 show a pivoting means for the heaters.

25 In this invention the grinding is done in a circular chamber, the upper portion of which has serrated plates against which the material is forced by a plurality of swinging beater arms pivoted on a disk secured to 30 a rotatable shaft. A lower portion of the chamber is enclosed with a perforated screening, the size of the perforations depending upon the fineness to which the material is to be reduced.

35 Referring now more particularly to the drawing, the numeral 1 designates generally a base with upstanding sides and with a central opening 2 at the bottom through which the pulverized material is delivered.

40 Hinged on a pivot 3 at one side of the top of the base is a cover 4 preferably semi-circular in transverse section which has an opposite flange 5, with notches 6 therein by means of which it may be bolted or otherwise fastened to the base at the side opposite the hinge. The stud bolts 7 may project upwardly from the base at this side and the flange 5 may be engaged in the ordinary manner by nuts 8.

50 Secured to the inside of the cover 4 are a plurality of curved pieces 9 which preferably fit the inside cover, and are formed with serrations or teeth 10. These pieces 9 are preferably made removable separately by being separately connected to the inside

of the cover by any suitable fastening devices such as screws 11, so that plates with different serrations can be inserted, if desired.

At the ends of the base member 1 are 60 semi-circular grooves 12 of about the same diameter as the cover 4, and into these grooves a screen 13 is insertable from either end of the groove when the cover 4 is turned back or open, and it is obvious that screens 65 of different fineness of mesh can be employed to insure that the material which passes therethrough is of a predetermined degree of fineness.

At one end of the machine preferably 70 adjacent the top of the cover 4 is an inlet 14 for the material to be ground which, after it passes through the beating and grinding operation is delivered through the screen 13 and through the opening 2 in the 75 base 1.

A shaft 15 is mounted in bearings at the ends of the base 1 so that the cover will fit closely thereover at the ends of the base and attached to the shaft are a plurality of 80 disks or drums 16 and 17. These disks are spaced a slight distance apart, and mounted upon pintles or shafts 18 extending between the disks are grinding beaters 19. These beaters are preferably spaced an equal distance 85 apart between each pair of disks; for example, there may be four beaters pivoted apart at points one quarter of the distance around the disk. The beaters between the next two disks may be spaced apart the same 90 distance and in addition, are also staggered with respect to the beaters between the first two disks, continuing so on between each successive pair of disks so that they will in effect have a step by step or successive operation with respect to any longitudinal line of the cover.

In construction, each beater 19 preferably has a flat beating surface 20 at its forward side, that is, on the side which is foremost 100 when the shaft 15 is rotated, and it is pivoted between two adjacent disks upon a flattened portion 21 which fits easily between the disks so that the beater is free to rotate upon its pivot pin or shaft 18. Extending 105 at right angles to the flat face 20, and at a point just beyond the periphery of the disks 17 is a shoulder 22 which engages the outer faces of the adjacent disks 17 to limit the rotation of each beater about its pivot. 110

The forward position is, as clearly shown in Fig. 1 with the front side of the shoulders 22 in contact with the disks 17 and when the beaters are allowed to fall back they will do so only to the extent that the rear end of the shoulders 22 engage the peripheral face of the disks 17.

These beaters are preferably in the form of a sector, and the outer peripheral edge is formed with serrations or teeth 23 extending lengthwise parallel to the shaft 15 and parallel to the serrations 10 of the cover plates 9. The teeth of the beaters are preferably inclined, as shown, while the teeth of the stationary plates 9 in the cover may be of equal length on each side.

Another feature of great importance is that the distance from the pivot of each beater to the front peripheral angle thereof, designated by a in Fig. 1, is less than the distance from the pivot point to the rear peripheral angle designated by b . In other words, the beater is longer at the back than the front and the teeth 23 thereof are correspondingly graduated in distance from the front to the rear of each beater. Because of this fact, in the rotation of the grinding beater within the mill, a greater amount of material can occupy the space between the front angle of the grinding beater and the serrated plates of the mill, than if the beater were a flat bar, thereby causing a constant gradual movement of the material in the smaller space producing a quicker grinding action.

In mounting the beaters between the disks 16 and 17, the disks may be provided with perforations 24 which can be alined for the reception of short pivot pins 18 extending between them, as shown in Fig. 4. In order to mount or remove one of the beaters the pivot pin is moved laterally into one of the disks 17, the beater 19 is slipped in place or removed in a well known manner, and the pivot pin is held in place by means of a spring ring 25, also shown in Fig. 3 which is insertable through a perforation 26 in the pivot pin 18, like a cotter pin, the ring preferably having one extremity 27 which is bent inwardly and the other extremity which lies close to the adjacent portion of the ring. This ring lies between the beater 19 and one of the disks 17 and preferably extends beyond the periphery of the disk 55 so it can be inserted and removed manually, but cannot become loosened by accident because of the shape of the ring which will not permit disengagement from the pin except by manual means.

In operation, the material to be ground is introduced through the opening 14 and with the shaft 15 rapidly rotating in the forward direction as indicated by the arrow in Fig. 1, it is found that the material is first struck with the front face 20 of the

grinding beater and is then thrown outward against the grinding plates 9 of the mill from whence it rebounds to the second grinding surface consisting of the teeth 23 of the beater, then back and forth between the grinding plate 9 and the toothed edge 23 of the beater, making repeated impacts gradually becoming quicker and shorter as the material approaches the rear end of each beater until it escaped between the beater and the plate and is again engaged by the next beater. The rapidity of rotation, in order to secure the best results as found in actual practice must be relatively high and I have found that the machine operates very successfully at 3600 revolutions per minute with a drum or casing of about 20 inches diameter.

It is found in practice that the teeth of the beater are subject to considerable wear when the beater is in operation, and it is contemplated that the face 20 as well as the outer toothed surface 23 may be made in sectional form or removable for replacement. Grinding teeth of different shape may be used for different material or for grinding the same material to different degrees of fineness. Instead of mounting the beaters upon pivots, as shown, beater disks may be provided with outer surfaces corresponding to the toothed surfaces 23 arranged in varying distances from the center of the disk, but thus limiting the separate pivotal mounting of the beaters. This would still preserve the essential feature of the present construction by providing a beater with a grinding surface. It is obvious that other modifications may be made in the construction, combination and arrangement of the parts without departing from the spirit and scope of the invention.

With a construction of this kind it is found that any material can be reduced to the desired degree of fineness in the least possible time due to the successive and repeated graduation of the beater impacts.

I claim:

1. In a pulverizer, a pair of spaced disks having axial perforations which may be alined, a pivot pin slidable axially therein and long enough to extend between the disks, a beater mounted upon the pivot pin between the disks, the pivot pin having a transverse perforation, and a spring wire insertable through the perforation of the pivot pin disposed between the beater and one of the disks and extending between the periphery of the disk for manual engagement thereof to insert and remove the spring ring.

2. In a high speed centrifugal pulverizing machine having a lateral inlet through which the material is drawn by the suction created by the machine, the combination of an annular casing having transverse in-

- wardly projecting serrations, a shaft through said casing and relatively short grinding beaters pivotally mounted on said shaft, each of said beaters being made in substantially the form of a segment and having a flat radial forward beating surface and having transverse teeth on the peripheral surface, the arrangement being such that when the shaft is rotated at a high speed the material to be ground is first struck by the beater face and thrown against the serrations in the casing and is further acted upon by the teeth and serrations as it passes between the same.
- 5 3. In a machine of the character set forth, the combination of a casing having trans-
- verse teeth around the inner periphery, a shaft through said casing and grinding beaters pivotally secured to the shaft, said beater being such length that a plurality thereof is required to extend the length of the casing, said beaters having flat front faces for throwing the material outwardly against the serrations and having transverse teeth in their outer surfaces and means for rotating the shaft and beaters whereby the material will be thrown from the faces of the beaters against the serrated casing and will then be thrown back and forth between the teeth and the serrations for pulverizing the same.
